United States Patent Office.

MARTIN LANDENBERGER, OF PHILADELPHIA, PENNSYLVANIA.

Design No. 4,272, dated August 2, 1870.

DESIGN FOR A SHAWL FABRIC.

The Schedule referred to in these Letters Patent and making part of the same.

To all whom it may concern:

Be it known that I, MARTIN LANDENBERGER, of Philadelphia, in the county of Philadelphia and in the State of Pennsylvania, have invented a new and original Design for Shawl Fabric; and do hereby declare that the following is a full, clear, and exact description thereof, reference being had to the accompanying drawing and to the letters of reference marked thereon making a part of this specification.

The nature of my design is fully represented in the accompanying drawing.

A A represent a series of square blocks, followed by narrow strips B B, after which is again a series of square blocks A A. Next to this latter series of blocks A comes another series of square blocks, C C, of a darker color than the blocks A A. Then fol-

low oblong or rectangular blocks D D, then a strip E, and so on.

The fabric itself is made in a somewhat similar manner as the ordinary red flannel, the colors being immaterial, but mostly all the figures have spots dots of a darker color than the ground-work, and the configurations of the fabric run both ways, as shown.

What I claim is—

The design for a shawl fabric, as shown and described.

In testimony that I claim the foregoing, I have hereunto set my hand this 16th day of June, 1870.

MARTIN LANDENBERGER.
